CLAIM

The ornamental design for a water toy, as shown and described.

DESCRIPTION

FIG. 1 is a front and left perspective view of a water toy showing my new design;

FIG. 2 is a left view thereof;

FIG. 3 is a front view thereof;

FIG. 4 is a rear view thereof;

FIG. 5 is a top view thereof; and,

FIG. 6 is a bottom, front and right perspective view thereof. The broken line showing is for illustrative purposes only, and forms no part of the claimed design.
